ATTORNEY

UNITED STATES PATENT OFFICE.

ROBERT H. PENWARDEN, OF BEARDSTOWN, ILLINOIS.

ROD PROTECTOR.

Application filed August 11, 1926. Serial No. 128,660.

In truck constructions for freight cars the brakes on the different wheels are equalized by suitable levers and connecting rods, and the lever is fulcrumed at a point a little above the spring board and extends downwardly to a point below the said spring board where it is connected with a rod, which rod has its opposite end connected to a second lever, and the rod which connects the two levers hangs in a horizontal position. These rods are connected to the levers by pins and the pins frequently work loose, so that the rods fall onto the track and cause derailments of the car and damages to the track and rolling stock. It is, therefore, to be considered the object of this invention to provide an extremely cheap, easily attached and thoroughly effective means for supporting such connecting rods even when the same have been disassociated from connection with the levers.

To the attainment of the foregoing the invention consists in the improvement as hereinafter described and definitely claimed.

In the drawings:

Figure 1 is a bottom plan view of a truck to illustrate the application of my improvement thereon.

Figure 2 is a perspective view looking toward the upper face of the spring board and showing the manner in which the improvement is arranged thereon.

Figure 3 is an end view of the improvement.

Referring now to the drawings in detail, the numeral 1 designates an ordinary truck construction for freight cars and 2 the channeled spring board which extends across the truck and on which the coil springs of the car rest.

I do not believe it necessary to refer to the details of construction of the brake actuating means which are associated with these trucks as the same are well known in the art. The brakes for the different wheels of the car are equalized by suitable levers 3 and connecting rods 4 for said levers. The levers 3 are fulcrumed at a point a little above the spring board 2, as indicated by the numeral 5, and extend downwardly to a point below the spring board, the rod 4 being thus arranged below and transversely of the spring board. The rod 4 has its opposite ends widened and bifurcated to receive therein the ends of the

levers 3, pivot pins 6 passing through the arms thus provided and through the ends of the levers, and these pivot pins are usually engaged by cotter pins which, incident to the vibrations to which the truck is subjected, frequently become dislodged so that the pivot pins become loose and become lost. The result is that the rods 4 drop onto the track and in some instances have caused derailment of trains and in other instances have caused the trains to contact therewith and materially damage the road bed of the track.

In carrying out my invention I make use of a member which is formed from a single strand of spring wire and which includes a central body portion 7 that has its ends rounded to provide eyes 8 and from said eyes are formed extensions that provide the same with hooks 9. These hooks 9 are designed for frictional contact with the side flanges of the channeled spring board 2 so that the eyes 8 are arranged in a line with the said flanges directly below the spring board, and receive the connecting rod 4 therethrough. By this arrangement it will be seen that the connecting rod 4 will be at all times properly guided and effectively supported, even should the pivot pins which associate the levers 3 with the said rod become loosened or lost.

The simplicity and advantages of the improvement will, it is thought, be apparent to those skilled in the art to which such invention relates when the foregoing description has been read in connection with the accompanying drawings.

Having described the invention, I claim:

The combination with the wheeled truck of a freight car having the usual transversely arranged channeled spring supporting board, and the equalizing levers for the brakes, which latter are fulcrumed above the spring board, and the connecting rod which pivotally secures the oppositely disposed levers, of a support for the connecting rod, comprising a spring wire member having its ends rounded to provide eyes through which the connecting rod passes and the ends of the said eyes being extended to provide spring hooks which clampingly engage the flanged sides of the spring board.

In testimony whereof I affix my signature.

ROBERT H. PENWARDEN.
